UNITED STATES PATENT OFFICE.

WILLIAM R. KIRKPATRICK, OF BALTIMORE, MARYLAND.

AEROPLANE.

1,057,246.

Specification of Letters Patent. Patented Mar. 25, 1913.

Application filed May 12, 1911. Serial No. 626,786.

To all whom it may concern:

Be it known that I, WILLIAM R. KIRKPATRICK, citizen of the United States, residing in Baltimore, State of Maryland, 5 have invented certain new and useful Improvements in Aeroplanes, of which the following is a specification.

This invention relates to aeroplanes in general, but more particularly to a gravity-10 suspended car, which carries the motor and aviator, and from which the various mechanisms for propelling and guiding the car and causing its ascension and descent are readily accessible to the aviator.

15 The invention consists in providing certain new and novel mechanisms by which the car is suspended from the frame of the machine; and by which the car may be maintained in a true vertical position when the 20 machine is moving in a horizontal plane, or in a laterally tilted position.

25 The invention further consists in the novel construction and arrangement of the various mechanisms for propelling and guiding the aeroplane or machine, and for causing its ascent and descent, as will be hereinafter fully described in this specification, and briefly stated in the claims.

30 The chief object of the invention is to produce an aeroplane, whether of the mono or bi-plane type, in which the equilibrium of the car will be automatically maintained, whether ascending or descending, or tilted in a lateral direction by the force of the 35 wind.

Other objects of the invention will become apparent upon a complete disclosure thereof.

40 In the drawings—Figure 1 is a side elevation of my improved aeroplane, the rear portion of the frame being broken away; Fig. 2 is a front elevation of the same, the outer end of the plane framework being broken away; Fig. 3 is an enlarged horizontal section of the universal gear connection by which power is transmitted from motor to propeller; Fig. 4 is a side elevation of the same, showing the manner in which it is suspended from the center 45 bracket; Fig. 5 is a rear elevation of the universal connection, showing the power-transmitting sprocket and chain; Fig. 6 is a 50 rear elevation of the mechanism for inclining the front of the machine in either an "up" or "down" position, in ascending or descending; Fig. 7 is an en-

larged horizontal section of the same, on line 7—7 of Fig. 6; Fig. 8 is a similar section on line 8—8 of Fig. 6; Fig. 9 is a horizontal section taken just above the car, 55 showing a top plan view of the rudder steering mechanism; Fig. 10 is a side elevation of Fig. 9; Fig. 11 is a detail perspective view of the rudder and a portion of the steering mechanism, and Fig. 12 is a 60 diagrammatic top plan view of the aeroplane; Fig. 13 is a top plan view of the central structure of the aeroplane; and Fig. 14 is a top plan view of the platform or car. 65

Referring to the several views, the numeral 1 indicates a center casting having a number of arms projecting therefrom, to which arms are secured braces which support and strengthen the center structure, which is constructed of four rods 2, 3, 4, and 5, supported from the center casting by braces 2', 3', 4', and 5', the respective ends of said braces being secured to arms 2'', 3'', 4'', and 5'' of the casting, and to connections 6, 7, 8 and 9. Arising from each connection 6 and 9 is a vertical standard 10, and arising from each connection 7 and 8 is an outwardly-inclined standard 10'. The upper ends of the standards 10 are secured to six-arm connections 11 and said standards are connected together by a transverse rod 12. The upper ends of the standards 10' are secured to five-arm connections 13 and the standards 10 and 10' are connected together by longitudinal rods 14, while the 80 standards 10' are connected together by a transverse rod 15. 85

Secured to the outwardly-projecting arms of connections 6—7 and 11—13 is a suitably trussed frame 16, constituting one of the wings of the aeroplane, and secured to the outwardly-projecting arms of connections 8—9 and 10—11 is a suitably trussed frame 17, constituting the other wing of the aeroplane, both of which wings are provided 95 with the usual canvas covering. Secured to the rearwardly and outwardly-projecting arms of connections 6—9 and 11—11 is a suitably trussed frame 18 tapering to a point. 100

The numeral 19 indicates a propeller shaft journaled at its outer end in a bearing-block 20 supported by rods 21 and 22, which extend upwardly and outwardly from connections 7 and 8 respectively, said 110 shaft carrying suitable propeller 22. The inner end of the shaft is journaled in the

yoke 23 of a universal-joint 24, rotatably supported in bearings 25 of a hanger 26, which is divided longitudinally and bolted to a screw-threaded post 27, as clearly 5 shown in Fig. 4. The bar 28 of the universal-joint, to which the yoke is swiveled, is centrally bored, as shown at 29, into which the inner end of the propeller-shaft projects, and mounted on said end is a beveled 10 gear-wheel 30 which meshes with a combined gear and sprocket-wheel 31.

The numeral 32 indicates platform or car upon which the motor 33 and the operating-mechanism is located, and upon which the 15 aviator or operator is positioned. The platform is rectangular in shape and is preferably composed of bars 34 joined together by four-arm connections 35, and strengthened by braces 36 connected to a center structure 20 37. This center structure consists of four corner connections, to which the braces 36 are connected, joined together by rods 38 and universal joints 39 and 40. The platform is gravitationally suspended from the 25 universal-joint 24 by a hanger 41 consisting of four corner posts 42 connected together by braces 43, and secured to the respective corner connections of the center structure 37, the connection of the hanger with the 30 platform being strengthened by inclined braces or struts 44. The ends of the posts forming the hanger converge and are connected to a two-part strap 45 having arms 46, the parts being bolted together and the 35 arms bored to encircle the hub 47 of the bar 28 of the universal-joint 24. The platform or car is provided with suitable wheels 48, for permitting the aeroplane to be propelled on the ground, when desired, and to facilitate alighting.

The propeller shaft is driven by a sprocket-chain 49 running over the sprocket wheel, of the combined gear and sprocket-wheel 31, and a sprocket-wheel 50 on the 40 shaft of the motor 33.

Journalized in the outer ends of braces 52, extending rearward from opposite sides of the frame 18, is a shaft 53 provided with a central hollow hub 54 in which is pivoted a 50 rudder 51, the stem of the rudder, at its inner end being provided with a vertical slot 55. Mounted on the shaft 53 is a pulley 56 over which runs both ends of an operating wire or cord 57 to and around a pulley 58 55 mounted on a shaft 59 projecting from one of the screw-threaded plugs 60 which forms one of the journals of the bar 28 of the swivel 24, said shaft extending through the other screw threaded plug 61, which forms 60 the other journal bearing for the bar 28, and secured by a nut 62. The ends of the cord pass down the hanger 41 to within easy reach of the aviator, where they are secured to a pulley 63 mounted loosely on a tubular 65 shaft 64, rigidly secured in bearings 65 se-

cured to oppositely-disposed braces 66 of the hanger 41. The pulley is provided with an operating handle 67, and secured to the shaft, by any well-known means, is a collar 68 having a slotted arm 69 projecting therefrom, and a set-screw 70 passing through the slotted arm 69 serves to lock the pulley to the collar and thereby prevent its accidental movement.

Passing through the slot 55 of the rudder stem is a wire or cord 71, the ends of which pass over pulleys 72, pivoted at any desired point on opposite sides of the frame 18, over and around a pulley 73, loose on shaft 59, and thence down to a pulley 74 mounted loose on the fixed shaft 64, where it is fastened. The pulley 74 is also provided with an operating handle 75, and a collar 76, having a slotted arm 76', fixed on said shaft, and a set-screw 77 passing through said slotted arm serves to lock the pulley against rotation, when desired. The operating-wire 57 is used to manipulate the rudder in ascending or descending, while the operating-wire 71 is used to deflect the rudder laterally in turning from a straight course, and is effected by means of collars 71' and 72', one on each side of the rudder stem.

The mechanism for controlling the aeroplane in ascending or descending and in horizontal flight, assisted by the rudder, consists of a tubular member 78 and member 79 slidable within the tubular member. The lower end of the tubular member is connected to the center structure 37 by the universal joint 39, and journaled in a bracket 80, secured to the outer surface of said tubular member is a sprocket-wheel 81, the shaft of which is provided with an operating handle 82 within easy reach of the aviator. 100 Journalized in a bracket 83 secured at the upper end of the tubular member is a sprocket wheel 84, which is connected with sprocket-wheel 81 by a sprocket-chain 85. The slidable member is cross-shape in cross-section, 110 preferably hollow, and has one of its longitudinal ribs provided with rack-teeth 86 adapted to be engaged by a toothed wheel 87 mounted on the shaft of the sprocket-wheel 84. The other longitudinal ribs of the slidable member serve to guide the member in telescopic movement in the tubular member, 115 said movement being facilitated by a number of idler-wheels 88 pivoted in suitable brackets secured to the tubular member, 120 which project through slots 89 in the wall of said member engaging said ribs, as shown in Fig. 6. The slidable member is connected to a universal-joint 90 supported at the front of the machine by two rods 91 and 92 secured to connections 7 and 8, respectively, of the center structure of the aeroplane. In ascending, the slidable member is moved upward, by the sprocket-wheel and chain operating-mechanism, which causes the upward 125 130

tilting of the front of the aeroplane, and in descending, the slidable member is moved downward, causing the front of the aeroplane to be tilted downward, the former movement causing the machine to ascend and the latter to descend. The tubular and slidable members may be locked together to form a brace for holding the platform rigid with the aeroplane which is desirable when the machine is moving on the ground preparatory to ascending or in alighting, by a wheel operated brake 82' holding the shaft of sprocket-wheel 81 against rotation. A similar mechanism is employed to tilt the sides of the aeroplane, a tubular member 93 being connected, at its lower end, to the center structure 37 by the universal joint 40, and a member 94 slidable in the tubular member, the slidable member being connected to a universal-joint 95 supported by rods 96 and 97 secured to connections 8 and 9, respectively, of the center structure of the aeroplane, the movement of the slidable member being effected by the sprocket-wheels 98, 99; chain 100, and toothed wheel 101 engaging the teeth 102 of the slidable member, said slidable member being guided by the wheels 103 operating through slots in the wall of the tubular member, as in the tubular member 78. The means for locking the slidable member against movement is similar to that for holding the slidable member 79 against movement, and consists of a wheel operated brake 104.

By means of the universal connection between the aeroplane and the hanger, which supports the platform, the position of the hanger, and its attached platform, will always be in a true vertical line, and the aeroplane can be made to assume any angle, to the hanger, within a radius of forty-five to ninety degrees, without affecting the vertical position of the hanger, and by means of the said connection the hanger may rotate in a direction perpendicular to the movement of the propeller.

The movement of the aeroplane may be readily controlled by operating the slidable members 79 and 94. Assuming that the flight of the machine is on a horizontal plane, a downward movement of the slidable member 79, which is at the front of the machine, will tilt the front of the aeroplane in a downward direction and the rear extension in an upward position, causing the machine to assume a descending position, while an upward movement of the slidable member 79 will cause the aeroplane to assume a reverse or ascending position. A downward movement of the slidable member 94 will tilt the aeroplane laterally, causing it to describe a circle to the right, while an upward movement of said slidable member will cause the aeroplane to describe a circle to the left.

Thus it will be seen that the movements of

the aeroplane may be controlled, independent of the rudder, by the manipulation of the slidable members 79 and 94, so that in case the steering mechanism should become in any way disarranged or out of order, the machine would not become unmanageable.

A retarding device in the shape of an ordinary self-opening parachute 105 may be attached to the center casting 1, as shown in the open position in Fig. 1 and in closed position in Fig. 2. The handle of the parachute is screwed into the top of the casting, and an operating cord 106, attached to a trigger 107 and extending down within reach of the aviator, is employed to release the holding catch. In case of an accident, the parachute is useful in retarding the downward flight.

A suitable railing 108 may be erected around the platform as an element of safety.

In constructing the frames of the aeroplane and platform or case, I prefer to employ tubular rods of aluminum, and to make the tubular and slidable members of the same metal, in order to secure lightness and strength.

It will be noted that the chief object of the invention is to produce an aeroplane of the mono or bi-plane type, incapable of being overturned while in flight, and in which a descention to the ground can be safely made should any of the vital parts of the machine become disarranged or broken, or the motor fail to work, the construction being such that the equilibrium of the car or platform will be automatically maintained in a vertical position, whether ascending or descending or whether the aeroplane be tilted in a lateral position. It will also be noted that the aeroplane, when tilted in a lateral direction, will be prevented from making any angle less than that fixed with the hanger, by reason of the hanger coming into contact with the lower part of the center structure.

Having thus fully described my invention what I claim is:—

1. In an aeroplane, the combination of a center-structure provided with oppositely-disposed planes and a rear extension, a platform or car suspended from the center-structure by a universal connection, a tubular member connected to the platform by a universal connection, a member slidable in the tubular member and connected to the center structure by a universal connection, and means for moving the slidable member to cause the tilting of the aeroplane in a longitudinal direction.

2. In an aeroplane, the combination of a center-structure provided with oppositely-disposed planes and a rear extension, a platform or car suspended from the center-structure, by a universal connection, a member slidable in a tubular member and con-

nected to the center-structure by a universal connection, means for moving the slidable member to elevate or depress the front of the aeroplane, and means for laterally tilting the aeroplane.

3. In an aeroplane, the combination of a center-structure provided with oppositely-disposed planes, a platform or car suspended from the center-structure by a universal connection, a tubular member attached to the front of the platform by a universal connection, a member slidable in the tubular member and attached to the front of the center-structure by a universal connection, 10 said slidable member adapted to be operated to tilt the front of the aeroplane in a vertical direction, a tubular member attached to the side of the platform by a universal connection, a member slidable in said tubular member and attached to the side of the center-structure by a universal connection, and means for operating said slidable member to tilt the aeroplane laterally.

4. In an aeroplane, a center-structure comprising a casting having outwardly and downwardly-projecting arms, an upper rectangular frame of connected rods, a lower rectangular frame of connected rods, both frames being connected together by corner- 25 posts and supported by brace-rods projecting from the arms of the casting, oppositely disposed planes and a rear extension, and a platform attached to the casting by a universal-connection.

5. An aeroplane comprising a center-structure composed of a casting having outwardly and downwardly-projecting arms, an upper rectangular frame of connected rods, a lower rectangular frame of connected rods, both frames being connected together by corner-posts and supported by brace-rods projecting from the arms of the casting, oppositely disposed planes, and a rear extension in combination with a platform attached to the casting by a universal-connection, and means for tilting the aeroplane in a vertical direction, and mechanism for tilting the aeroplane in a longitudinal direction, said mechanism comprising two 40 members, one of which is connected by a universal-connection to the platform and the other by a similar connection to the center-structure, one of said members being slidable, and means for moving the slidable member.

6. An aeroplane comprising a center-structure composed of a casting having outwardly and downwardly-projecting arms, an upper rectangular frame of connected rods, a lower rectangular frame of connected rods, both frames being connected together by corner-posts and supported by brace-rods projecting from the arms of the casting, oppositely disposed planes, and a rear extension, in combination with a plat- 65

form suspended from the casting by a universal-connection, and mechanism for tilting the aeroplane laterally or sidewise, said mechanism comprising a tubular member connected to the platform by a universal-connection, a slidable member connected to the center-structure by a similar connection, and means for operating the slidable-member.

7. An aeroplane comprising a center-structure composed of a casting having outwardly and downwardly-projecting arms, an upper rectangular frame of connected rods, a lower rectangular frame of connected rods, both frames being connected together by corner-posts and supported by brace-rods projecting from the arms of the casting, oppositely disposed planes, and a rear extension, in combination with a platform suspended from the casting by a universal-connection, means for tilting the aeroplane in a vertical, longitudinal direction, said means comprising two members, one slidable within the other, one member being connected to the platform by a universal connection and the other to one end of the center-structure by a similar connection, and means for operating the slidable-members, and means for tilting the aeroplane laterally or sidewise, the said means comprising a tubular member connected to the platform by a universal-connection and the other to one side of the center-structure by a similar connection, and means for operating the slidable-member.

8. An aeroplane having in combination, a center-structure, a rear extension provided with a rudder, means for operating the rudder in a vertical direction, means for operating said rudder laterally, a propeller arranged at the front of the aeroplane, a platform or car suspended from the center-structure by a universal-connection, a motor for driving the propeller, means for directing the aeroplane in an upward or downward flight, consisting of a tubular member and a member slidable therein, the tubular member being connected to the platform or car by a universal-connection and the slidable-member connected to the center-structure by a similar connection, and means for operating the slidable member.

9. An aeroplane having in combination, a center-structure, a rear extension provided with a rudder, means for operating the rudder laterally, a propeller arranged at the front of the aeroplane, a platform or car suspended from the center-structure by a universal-connection, a motor for driving the propeller, means for tilting the aeroplane laterally, consisting of two members, one slidable within the other, one member being attached to the side of the center-structure by a universal connection and the other member connected to the platform by a simi- 130

lar connection, and means for operating the
slidable-member.

10. An aeroplane having in combination, a
center-structure, a rear extension provided
5 with a rudder, means for operating the rudder
vertically, means for operating it later-
ally, a propeller arranged at the front of the
aeroplane, a platform or car suspended from
the center-structure by a universal-connec-
10 tion, a motor for driving the propeller, a
tubular-member connected to the platform or
car by a universal-connection, a slidable-

member connected to the center-structure by
a similar connection, means whereby the
slidable-member may be operated to tilt the 15
aeroplane in a vertically-upward or down-
ward direction, and mechanism for tilting
the aeroplane laterally.

In testimony whereof I affix my signature
in presence of two witnesses.

WILLIAM R. KIRKPATRICK.
